REVOLVING DOOR SAFETY SYSTEM
Thomas Pace, 253 W. 73rd St., New York, N.Y.
Filed Feb. 12, 1965, Ser. No. 432,115
5 Claims. (Cl. 109—8)

This invention relates to a revolving door safety system and in particular is directed to a revolving door locking mechanism for holding fast a revolving door in response to an intelligence stimulus initiated by a desire to intercept and apprehend an interloper or thief.

In banks, hotels and other institutions dealing with the general public and wherein valuable and the like are likely to be stored, there is a temptation on the part of the criminal oriented to partake of such valuables through the connivance of forceful means, such as guns, threatening notes, and etc., and thereafter abscond through the general public entrance into the ambient surroundings of the community.

Invariably, the entrance and exit doors of such institutions are revolving doors, since they appear to be the most convenient and reliable from a view of operation, space, drafts and space occupied. Such doors and their operation as to the apprehending of absconding thieves are the subject matter of the instant application.

In general, the invention consists of a revolving door having at the upper portion thereof an electrically driven locking mechanism, remotely operated by a person having access to the control mechanism, which locks the doors in a position so as to trap anyone within the confines of the revolving door between the outside area and the area inside the building. The release of such mechanism, to free the locking mechanism and thereby permit the door to revolve, is also remotely controlled so as to permit the locking mechanism to re-cycle and set for another cycle of operation.

It is therefore an object of the invention to provide an improved safety control system for apprehending offenders.

Another object of the invention is to provide a revolving door remotely controlled locking system for confining undesirables within the confines of the said revolving door.

Another object of the invention is to provide revolving door safety system which can be remotely controlled for locking the said revolving door and thereafter released for re-cycling to permit a new cycle of operation.

Other objects and advantages will be readily discernable from a reading of the specifications and a study of the accompanying drawings and wherein;

FIGURE 1 shows a plan view of a public accommodation enclosure and a revolving door for the convenience of incoming and outgoing patrons.

FIGURE 2 shows an enlarged plan view of a revolving door similar to FIGURE 1 and a locking-release mechanism according to the invention.

FIGURE 3 shows a sectional view through the line 3—3 of FIGURE 2.

FIGURE 4 shows a partial plan view of FIGURE 3 and the lock-release mechanism in engagement position.

FIGURE 5 shows a detail of the release mechanism for disengaging the locking device from the revolving door.

FIGURE 6 shows a schematic control diagram for operating the lock-release mechanism according to the invention.

FIGURE 7 shows a circumferentially slotted cam-type plate revolving attachment for receiving in locking engagement the lock-release mechanism.

Now referring to the drawings, keeping in mind that similar or like parts will be designated by the same reference numbers, there is shown particularly in FIGURES 1 and 2 an accommodation enclosure 1 for the general public

2

where access thereto and exit therefrom is through a revolving door type structure 2.

In general, the revolving door structure 2 is comprised of a cylindrical central column or beam 3 to which is attached four elongated panels 4 arranged in a cross-like fashion so that the panels are orthogonal to each other and encompass quarter sections of a circular plain transverse or radial to the column. The four panels and column revolve as a single unit within a cylindrical-like shell or enclosure 6. The said cylindrical-like enclosure 1 comprises a pair of oppositely spaced quarter wall segments 7 and 8, each having an arc whose length encompasses a quarter segment of the revolving door. The other quarter segments 9 and 10 are open spaces for exposure internally and externally of the enclosure 1, through which the general public appears and uses.

Atop the revolving door structure 2 and attached to the upper portion of wall segments 7 and 8, there is an enclosure 11 having disposed therein a lock and release mechanism, as shown in FIGURES 2 and 3, and forming in part the subject matter of this invention. In particular there is shown in said enclosure 11 a base 12 having centrally oriented a hole 13 for receiving structural revolving door column 3, the said column being pivotally supported in a bearing support 14 atop of said hole and base.

The bearing support 14 has reposing thereon along one of its exposed surfaces 15a, a cantilever-like slotted cam plate 15. The cam plate 15 is centrally drilled to permit the journailling of column 3 therein and therethrough. The column and cam plate are each axially slotted at quarterly spaced positions 16 to permit key members 17 to snugly repose in keyways defined by said slots and thereby permitting the rotation of the cam plate with the rotating column and door as a single integrated unit. Along the outer periphery of said cam plate there are slots 18 spaced at quarterly intervals and each disposed to lie at a position midway between the angles formed by a pair of adjacent panels forming the revolving door when the said plate is positioned on the supporting column 3. The outer periphery of the cam plate between adjoining slots 19 takes on a spiral-like contour so that adjacent sides 20 and 21 of each slot are unequal in a radial direction. The reason for this will be described later.

Along the base 12 of the enclosure 11 and attached thereto along the outer periphery thereof is a relay operated mechanism assembly 22 comprising a solenoid coil 23 wound about an elongated plunger or armature arm 24, and supported by a pair of spaced apertured brackets 25 and 26. The bracket support arm guides the plunger in a direction towards the said cam plate so as to position same in one of the cam slots to effect the stoppage thereof in its rotational movements corresponding to the movements of the revolving door.

Mounted to the plunger arm 24, intermediate the said spaced apart brackets 25 and 26 is a disc-like washer 27 forming the support for coil spring 28 surrounding the said plunger between the support washer and bracket 26. Inward movements of the plunger, away from the cam plate, compresses the spring 28, and release of the said plunger from the holding action initiated by the solenoid 23 causes the spring to expand and force the plunger arm outward toward the cam plate and into one of the slotted portions thereof.

Attached to the plunger arm 24 intermediate the solenoid coil 23 and bracket 26 is a shoulder piece or bracket 29, radially protruding from the plunger and disposed to intercept a holding plate 30 forming a portion of a holding relay device 31 mounted to the base 12 of enclosure 11 and positioned transversely to relay mechanism 22.

The holding relay device 31 comprises a holding solenoid coil 32 surrounding an elongated armature plunger arm 33 which is coextensive with a heavier arm 34 and which is in turn supported by a pair of spaced apart apertured brackets 35 and 36. At the extremity of said arm 34, remote from the solenoid coil 32, there is pivotally attached thereto within a recessed portion 35 thereof, a holding plate 30, pivotally supported about the center thereof by support pin 37. The holding plate has freedom of motion in a counter-clockwise direction to an angular position as defined by bearing surface or stop 38 forming the extremity of arm 34. The holding plate is restored to its original position, the axial direction of the arm 34, by a restoring spring 39. The plate is fixedly held in this axial direction by that rear portion of the plate 40 residing on surface 41 forming a side of the recess 35.

In operation, while the revolving door is free to rotate, relay mechanism 22 has its plunger arm 24 withdrawn, against the pressure of coil spring 28, it being held in this position by the abutment of the shoulder bracket 29 attached thereto with the holding plate 30 forming a part of the holding relay device 31. To release plunger 24, momentary contact control button 42, shown in control diagram of FIGURE 6, is impressed so as to actuate solenoid 31. The actuation of coil 31 causes plunger 34 to withdraw against a normally operative restoring force thus permitting the disengagement abutting bracket 29 and plate 30 and the plunging forward of arm 24 in a direction to intercept the cam plate. The plunger arm engages the first available cam slot, thereby causing the revolving door to stop immediately. It may be possible at certain times that because of the high speed of the revolving door, the plunger will not immediately intercept the first available slot. To avoid this limitation, the cam plate has a spiral contour so that the plunger will have a high protruding wall slot to intercept the driving plunger.

Because of the orientation of the cam plate relative to the revolving door panels, the door will stop at a position where each of the opposing enclosure walls 7 and 8 will embrace opposing one-quarter segments of the revolving door, the other segments being exposed to both the internal and external enclosure parts. The wall segments of the revolving door, under lock conditions, permits the retention and confinement of any persons within the sphere occupied by the wall and door segments to the detriment of any undesirable persons.

It may be appreciated, however, that confinement will ordinarily take place within the segment 49 bounded by wall portion 7 and that segment defined by door panels 50 and 51. When such undesirables are so apprehended, it is possible to have innocent persons confined in that segment 52 diametrically opposed to segment 49. To release such innocent persons, a door 53 is provided which opens into the enclosure.

To release the locking mechanism, momentary contact push-button 54 is impressed to permit the energization of relay coil 32, thereby pulling back plunger 24, until its shoulder bracket 29 intercepts plate 30. Plate 30 undergoes an angular movement, as shown in FIGURE 5, until the bracket 29 is made freely clear thereof, at which time the plate goes back again to its original position. The plunger 24 thereafter again, through the abutment of bracket 29 and plate 30, is free from the cam plate slots 65 and is ready for another cycle of operation.

There is shown in FIGURE 7 another arrangement of the cam slot and plunger. In particular, the slots and plunger tip are tapered to form a more positive mesh when they are operatively engaged.

It may be appreciated that certain changes in form and design may be made without detracting from the true purpose and intent of the invention as defined and embodied herein.

Having defined the invention, what is claimed is:

1. In an enclosure having a revolving door for the entrance and exit of the general public, a remote control door lock and release system comprising,
  - (a) a revolving door including a central supporting column,
  - (b) an enclosure above said door and disposed to receive and support the column at the upper extremity thereof,
  - (c) a slotted cam plate within said enclosure and supported by said column and disposed to rotate therewith in a predetermined position,
  - (d) means including a pair of solenoidally remotely operated interacting elongated plunger mechanisms each supported by said enclosure, one of said mechanisms intercepting said cam plate along the slotted portion thereof in response to said door lock remote control actuating the other solenoid operated mechanism to lock the door in a predetermined position, said other plunger mechanism being disposed to interact with the first plunger mechanism in response to the door release control for actuating the solenoid of said first plunger to permit the release of said first plunger from the slotted cam plate and thereby unlock the door to permit another cycle of operation.
2. In an enclosure according to claim 1 and wherein said plunger means is a relay operated armature surrounded by resilient means disposed to urge the plunger in a direction to intercept the cam slotted plate.
3. In an enclosure according to claim 2 and wherein said resilient means is a coil spring.
4. In an enclosure according to claim 1 and wherein said release means includes a relay actuated arm disposed to disengage from said plunger means.
5. In an enclosure having a revolving door for the entrance and exit of the general public, a remote control door lock and release system comprising,
  - (a) a four-quarter segment revolving door including a central supporting column,
  - (b) an enclosure above said door and disposed to receive and support a column at the upper extremity thereof,
  - (c) a cam plate having tapered slotted portions along the periphery thereof, each slot positioned midway each segment of the door within the said enclosure and supported by said column and disposed to rotate therewith in a predetermined position,
  - (d) means including a pair of solenoidally remotely operated interacting elongated plunger mechanisms each supported by said enclosure, one of said mechanisms intercepting said cam plate along the slotted portion thereof in response to said door lock remote control actuating the other solenoid operated mechanism to lock the door in a predetermined position, said other plunger mechanism being disposed to interact with the first plunger mechanism in response to the door release control for actuating the solenoid of said first plunger to permit the release of said first plunger from the slotted cam plate and thereby unlock the door to permit another cycle of operation.
